DESK

Irving Richard Cornish, Elmhurst, Ill., assignor
of one-third to John Warren Paxton, and one-
third to George Noble Paxton, both of Bloom-
ington, Ill.; Arlie L. Paxton, and The National
Bank of Bloomington, executors of said George
Noble Paxton, deceased

Application December 31, 1943, Serial No. 516,321

7 Claims. (Cl. 45—70)

This invention relates to an improved desk construction, and more particularly, to an improvement in flat top desks such as are generally in use in offices and elsewhere.

The main objects of the invention are to provide a desk in which the entire area of the desk top is within reasonably convenient reach of a person sitting at the front or back of the desk; to provide a desk structure in which equipment built into the desk, such as a file for example, is presented in a more convenient position than are the files and the like in conventional desks; to provide a desk embodying the indicated improved features which will have a pleasing and attractive appearance and which may be made strong and sturdy at a cost not materially greater than the cost of producing conventional desks of equivalent quality.

Other objects and advantages of the invention will be understood by reference to the following specification and accompanying drawings (two sheets) wherein there is disclosed a desk embodying a selected form of the invention.

In the drawings,

Fig. 1 is a front perspective view;

Fig. 2 is a plan, certain portions being broken away to more completely illustrate the structure;

Figs. 3 and 4 are sections respectively on the lines 3—3 and 4—4 of Fig. 2.

As shown in the drawings, the improved desk embodies a flat top 5, and a pair of pedestals 6 and 7 respectively. The pedestals 6 and 7 may be of substantially like construction except that one is right-hand and the other left-hand.

Each pedestal is of generally rectangular form in horizontal plan or cross-section. Each embodies an inner side wall 8, a front 9, an outer side wall 10, a back wall 11 and a wall portion 12 connecting the adjacent ends of the inner wall 8 and rear wall 11. The inner and outer side walls of each pedestal are in substantially parallel relation to each other as are also the front and back of the pedestals. The various walls are interconnected by suitable means including, where desired, corner posts indicated at 13 which are extended downwardly to form supporting legs 14.

The pedestals 6 and 7 are angularly arranged as shown in such position that their inner side walls 8—8 are disposed in rearwardly converging relation to each other, and the front and rear walls of one pedestal at a rearwardly and outwardly disposed angle so that the pair of front and rear walls are in rearwardly and outwardly diverging relation to each other. The connect-

ing wall portions 12—12 are so arranged that they are substantially parallel to each other as shown.

The pedestals may be interconnected by a wall panel 15 extending between the walls 12—12 near their rearward ends and the said pedestals are further connected by the desk top 5 which overlies the areas of both of the pedestals and the spaces therebetween. The top may be rigidly secured to the pedestals in any suitable manner well known in the art. Also, the details of attachment of the various wall panels to each other and to the leg posts of the pedestals may be in keeping with ordinary desk construction practice wherefore such details are not herein illustrated.

The desk top has its central front edge portion 16 extending between the inner front corners of the pedestals, preferably although not necessarily, in a substantially straight line and in proximity to the plane of the front of the desk as determined by the plane of the inner front corners of the pedestals. The desk top also has front edge portions 17—17 in proximity to and in parallel relation to the plane of the fronts of the respective pedestals and side edge portions 18—18 similarly related to the outer side walls 10 of the pedestals. The top preferably extends rearwardly beyond the rear outer corner posts of the pedestals so as to provide a ledge portion 19 of such width as to facilitate occupancy of the rear portion of the desk by a person sitting with his or her knees under said ledge portion. Under the rear ledge portion of the desk top there may be provided a strengthening rail 20 suitably secured to the underside of the desk top and serving also to improve the general appearance of the desk.

Each pedestal of the desk may be equipped with suitable work-holding drawers, such as represented at 21. A desired number of said drawers may be provided depending more or less upon the required depth of the drawers. The rearwardly converging pedestal arrangement makes the mounting in the pedestal of file containers or boxes represented at 22 particularly desirable. Said file boxes are preferably of a pivotally or tiltably mounted type, such as disclosed in detail in co-pending application, Serial No. 484,392, John Warren Paxton, George N. Paxton and Irving R. Cornish, inventors. In general, such file boxes comprise front and bottom walls 23 and 24 respectively and end walls 25—25, said file boxes being mounted in the pedestals for rocking movement by means of a pair of cross links 26 and 27 which are pivotally mounted as

shown at 28 and 29 on the end walls of the file box, and pivotally mounted as indicated at 30 and 31 on the adjacent side walls of the respective pedestals. The file boxes, mounted as above described, swing from closed position as illustrated in the left-hand pedestal of Fig. 1, to the open position illustrated in the right-hand pedestal of Figs. 1 and 3. It will be observed that in the open position, the file box extends rearwardly and outwardly at an angle relative to the plane of the central front portion of the desk so that a person occupying the front of the desk may conveniently examine the contents of the file box without turning away from the desk to such a large degree as is necessary in conventional desks in which the drawers and file boxes pull out perpendicularly from the plane of the normal front of the desk. This is a substantial convenience for any person who does a great amount of work with files kept in a desk file.

A drawer such as indicated at 32, may be provided in the central front portion of the desk more or less in keeping with conventional desk construction, and sliding shelves 33-33 may similarly be provided in the upper portions of the pedestals. The sliding shelves will, in the present construction, pull out in a substantially perpendicular relation to the fronts of the respective pedestals. Because of the angular position of the pedestals and the corresponding angular position of the sliding shelves 33 when pulled out into useable position, the person occupying the desk has comparative freedom of movement between said shelves instead of being more or less boxed in between a corresponding pair of parallel shelves in a conventional desk of normal size. This is a further advantage of the angular disposition of the pedestals.

Suitable framework, indicated at 34, may be provided between the central front drawer 32 and the angularly disposed inner side walls 8 of the pedestals to maintain a completely finished appearance and, if desired, the triangular spaces enclosed by said framework may be occupied by smaller triangular drawers.

The described desk construction provides a number of utilitarian conveniences, such as already mentioned, and in addition, provides a desk having a top area of which substantially all portions are much more easily reached by an occupant of the desk than is the case in conventional rectangular top desks. Furthermore, the angular ends of the desk facilitate certain arrangements of a plurality of desks which conserve floor space.

Changes in the described construction may be made without departing from the spirit of the invention as defined in the appended claims.

I claim:

1. A desk comprising a top and a pair of pedestals supporting said top, the pedestals being of generally rectangular form in horizontal section and having storage space therein said pedestals being disposed in rearwardly converging relation to each other, whereby there are provided spaces between the pedestals which are wide at the front and back of the desk and which taper inwardly to smaller width intermediate the front and back of the desk, said pedestals having relatively spaced, substantially parallel wall portions respectively connecting the inner side and rear walls of the respective pedestals, said parallel wall portions providing leg space extending inwardly from the inner end of said

front, inwardly tapering space, said top overlying said pedestals and said spaces.

2. A desk comprising a top and a pair of pedestals supporting said top, the pedestals being of generally rectangular form in horizontal section and having storage space therein said pedestals being disposed in rearwardly converging relation to each other, whereby there are provided spaces between the pedestals which are wide at the front and back of the desk and which taper inwardly to smaller width intermediate the front and back of the desk, said pedestals having relatively spaced, substantially parallel wall portions respectively connecting the inner side and rear walls of the respective pedestals, said parallel wall portions providing leg space extending inwardly from the inner end of said front, inwardly tapering space, said top overlying said pedestals and said spaces and extending rearwardly beyond the rear, outer corners of said pedestals so as to provide a ledge extending substantially the entire length of the rear of the desk.

3. A desk comprising a top and a pair of pedestals supporting said top, the pedestals being of generally rectangular form in horizontal section and having storage space therein said pedestals being disposed in rearwardly converging relation to each other, whereby there are provided spaces between the pedestals which are wide at the front and back of the desk and which taper inwardly to smaller width intermediate the front and back of the desk, said pedestals having relatively spaced, substantially parallel wall portions respectively connecting the inner side and rear walls of the respective pedestals, said parallel wall portions providing leg space extending inwardly from the inner end of said front, inwardly tapering space, said top overlying said pedestals and said spaces and having a central front edge portion extending from the inner front corner of one of said pedestals to the corresponding corner of the other pedestal, front edge portions beyond said central portion and substantially parallel to the planes of the fronts of said pedestals, end edge portions substantially parallel to the outer sides of said pedestals, and a rear portion extending rearwardly beyond the rear outer corners of said pedestals so as to provide a ledge extending substantially the entire length of the rear of the desk.

4. In a desk, the combination of an elongated desk top, and hollow pedestals disposed under the end portions of said desk top and containing storage facilities, said pedestals having substantially parallel front and rear wall portions and substantially parallel inner and outer side wall portions disposed at substantially right angles to said front and rear wall portions, the pedestals being disposed under said top in such angular relationship to each other that the inner side walls extend rearwardly from the front of the desk in converging relationship to each other and the rear walls extend forwardly from the rear of the desk in converging relationship to each other, whereby there is provided leg space under both the front and back portions of the desk top and between said pedestals, the converging pedestal walls which extend rearwardly from the front of the desk being disposed at a smaller angle to each other than the converging pedestal walls which extend forwardly from the back of the desk, whereby the leg space under the back portion of the desk extends lengthwise of the desk to a greater extent than the leg

space provided under the front portion of the desk, said desk top having end edges in substantially parallel relation to the front and outer side walls of the respectively adjacent pedestals.

5. In a desk, the combination of an elongated desk top and hollow pedestals disposed under the end portions of said desk top and containing storage facilities, said pedestals having inner, and rear, side wall portions which converge respectively from widely spaced relation at the front and back of the desk to less widely spaced relation intermediate the front and back of the desk, whereby there is provided leg space under both the front and back portions of the desk top and between said pedestals, the converging pedestal walls which extend rearwardly from the front of the desk being disposed at a smaller angle to each other than the converging pedestal walls which extend forwardly from the back of the desk, whereby the leg space under the back portion of the desk extends lengthwise of the desk to a greater extent than the leg space provided under the front portion of the desk.

6. In a desk, the combination of an elongated top and hollow pedestals disposed under the end portions of said desk top and containing storage facilities, said pedestals having inner, and rear, side wall portions which converge respectively from widely spaced relation at the front and back of the desk to less widely spaced relation intermediate the front and back of the desk, whereby there is provided leg space under both the front and back portions of the desk top and between said pedestals, the converging pedestal walls which extend rearwardly from the front of the

desk being disposed at a smaller angle to each other than the converging pedestal walls which extend forwardly from the back of the desk, whereby the leg space under the back portion of the desk extends lengthwise of the desk to a greater extent than the leg space provided under the front portion of the desk, the back portion of said top projecting rearwardly beyond the rearmost portions of said pedestals so as to increase the rear to front dimension of the leg space under the back portion of the desk.

7. In a desk, the combination of an elongated desk top and hollow pedestals disposed under the end portions of said desk top and containing storage facilities, said pedestals having inner, and rear, side wall portions which converge respectively from widely spaced relation at the front and back of the desk to less widely spaced relation intermediate the front and back of the desk, whereby there is provided leg space under both the front and back portions of the desk top and between said pedestals, the converging pedestal walls which extend rearwardly from the front of the desk being disposed at a smaller angle to each other than the converging pedestal walls which extend forwardly from the back of the desk, whereby the leg space under the back portion of the desk extends lengthwise of the desk to a greater extent than the leg space provided under the front portion of the desk, said desk top having end edges in substantially parallel relation to the front and outer side walls of the respectively adjacent pedestals.
